UNITED STATES PATENT OFFICE.

SAMUEL W. DOUGLASS, OF NEW YORK, N. Y., ASSIGNOR TO JARVIS B. EDSON, OF SAME PLACE.

PROCESS OF AND APPARATUS FOR THE FORMATION OF DEEP WELLS.

SPECIFICATION forming part of Letters Patent No. 290,546, dated December 18, 1883.

Application filed October 24, 1883. (No model.)

To all whom it may concern:

Be it known that I, SAMUEL W. DOUGLASS, a citizen of the United States, residing at the city, county, and State of New York, have invented new and useful Improvements in the Process of and Apparatus for the Formation of Deep Wells, of which the following is a specification.

This invention relates to that class of improvements in which wells or drill-holes are to be made in rock formations overlaid with quicksand, sand, gravel, marl, &c., by passing pipes or tubes through such intervening materials under the aid of a continuous or substantially continuous stream of water, under sufficient pressure, discharged at the lower end of the said tubing, as described in United States Patent No. 277,695, and dated May 15, 1883, and issued to Jarvis B. Edson, whereby the materials encountered are moved, and the well-pipe allowed to descend until rock or resistance is reached requiring the operation of drilling. To provide for and facilitate such drilling operation within said tubes is one feature of this invention, although additional features consist in combining a peculiar kind of split sleeve-coupling having valves, packing-boxes, glands, rods, &c., with each section of tubing in such a manner that additional sections of pipe may be added from time to time as the same settles into the hole, and without stopping the pressure of continuously flowing water through said pipe, the said split coupling allowing drilling or boring tools to be operated within said pipe during the continuance of such flow of water; and the invention further consists in combining a peculiar valve in the top of a drilling or boring barrel, so as to allow the water to pass down through the same by its water-ways from the drill-rods, but not to pass from the boring-tubes or barrels up into said drill-rod, for the purpose hereinafter set forth.

The invention further consists in combining with the sleeve-couplings tie-rods or turn-buckles, for the purpose also hereinafter set forth; and the invention further consists in combining with the split sleeve-coupling suitable water-conduits and a three-way cock for operating the same.

In the accompanying drawings, Sheets 1

and 2, like letters of reference represent similar parts.

In Sheet 1, Figure 1 represents a single length of pipe partially inserted in the ground and provided with a screw-coupling, B, at its upper end, and secured by a split sleeve-coupling, C. The coupling C has three branches, D E G. D and E have packing-glands for receiving and securing the pipe or tube A and F. The branch G receives water from the conduit H and three-way cock I. The common coupling, B, rests on lugs or shoulders formed on the sleeve-coupling C. K represents a double-faced hinged valve, which seats at L L and M M. The inlet to cock I is at J, where it receives the water, under pressure, from pump or other source of supply. The branch Q delivers to the split coupling C. Hand-lever U is for directing the flow of water. The split coupling-sleeve C is similar in all respects to the split sleeve-coupling C. F represents a length of pipe in position to be screwed into coupling B. N represents tie-rods and turn-buckles (the latter not shown) for connecting the two split couplings C and C'.

Fig. 2 is a cross-section showing bearings A and A for the tie-rods N N, and b b the joint made by the two halves of the split coupling and its connecting-bolts. Fig. 2 also shows c c, the two halves of the split glands, and d d, the bolts for securing said glands.

In Sheet 2, Fig. 3 represents a top or plan view of the gland V, with the drill-rod inserted.

Fig. 4 represents the upper part of the split sleeve-coupling C, inclosing the pipe F at its upper end, having inserted in it a boring-tool, consisting of bit e, boring-barrel f, with check-valve g, drill-rod h with flush joint-couplings i. The upper end of drill-rod h is surrounded by the packing-box x and gland j.

Fig. 5 represents the upper part of the split sleeve-coupling C, surrounding the pipe F at its upper end, which has inserted in it the drilling-bit, part of the cable or rope l, and part of the working barrel or gland m, the barrel containing and clamping the rope l, and being surrounded by the packing and gland v. The apparatus thus described is not only intended for obtaining pure water by washing, boring, or drilling deep wells, but is also adapted to and useful for the purpose of reach-

ing and obtaining gas and oil from natural sources of supply found in the earth. It is also useful for sinking pipes to be used as "working-barrels" for pumping, or into which 5 suitable pumping apparatus may be lowered and located for deep-well pumping, whether such pumping be for obtaining oil or water.

The operation is as follows: The split sleeve-coupling C, being placed about the end of a 10 piece of pipe and coupling thereon, so that the coupling shall rest on the lugs described, is bolted together and the packing-gland D set up. Water-connection is then established through branch G, conduits H, and three-way 15 cock J, from the source of water-supply under pressure. The pipe so provided is raised into position and water forced from the pump (or otherwise) through the valve I into the sleeve-coupling C, thereby moving valve K against 20 its upper horizontal seat, L, and passing down and out at the bottom of the pipe A, thus removing the material and allowing the pipe A to settle into the hole so formed and ready for the addition of more pipe. This is 25 accomplished by providing a pipe as in the first instance, and having placed about its coupling and end a split sleeve-coupling like the one previously used, and, having made its packing-gland tight, it is to be hoisted into 30 position directly over the last split coupling used. When in position and the lower end entered into the coupling previously used, the tie-rods N are to be placed in the holes provided for them in the flanges of the two split 35 sleeve-couplings and set tight. The packing-boxes being made tight and the conduit for water being established, as before, with the remaining outlet from the three-way cock I, the lever U is shifted so as to change the direction 40 of the incoming water and cause it to ascend and then descend through the split sleeve-coupling and the pipe last added. Changing the direction of the water, as just described, tightens the upper swinging valve against its 45 horizontal seat and the lower swinging valve against its vertical seat. The tie-rods N are to be contracted by running down the nuts, (unless turn-buckles are used,) so as to enter the threaded end of the additional pipe 50 into the top of the common pipe-coupling, B, after which it is readily revolved and screwed "home," forming a complete coupling together of the two lengths of pipe, and admitting of the removal of the tie-rods and split sleeve-coupling device, after which the lowering operation 55 is to be resumed and the split coupling just released, attached to another length of pipe and placed in readiness to form the third section, and so the operation of adding the requisite 60 number of lengths of pipe becomes a continuous one, and without stopping the downward flow of the excavating-water or the employment of any special device for connecting the pipes together, and also without causing any 65 projecting obstructions upon the outside or upon the inside of the pipe, which latter is of great importance if drilling has to be done

within the pipe. Thus it will be seen that the continuous pipe will be readily lowered until large boulders or loose rock are encountered, 70 in which case it becomes necessary to insert a boring or drilling tool, the operation of which is as follows: Having the two split sleeve-couplings C in position and connected by tie-rods, as hereinbefore described, water is 75 caused to pass through the lowermost one, the action of which closes the swinging valve in the lower one against its upper horizontal seat. The valve K can now be removed from the upper split sleeve-coupling and the boring-tools, consisting of bit e, barrel f, drill-rod h, reduced stuffing-box j, all as shown in Fig. 4, 80 Sheet 2, inserted. The three-way cock I can now be shifted, so as to cause the water to descend by the upper split sleeve-coupling, and 85 the pipe made continuous and the lower split sleeve-coupling removed or not, as desired and occasion requires. The water now passes down the well-pipe and up outside in greater or less quantities, as desired; but in no event can the 90 water pass up through the drill-rod, owing to the check-valve shown at g, Sheet 2, Fig. 4.

Sufficient additional lengths of drill-rods can be attached and lowered through the gland and pipe, when boring machinery can be attached and set in operation. If the obstructions prove to be only a boulder or small mass of rock, the hole bored through it is to be reamed out large enough to allow the pipe to pass freely down, when the drilling apparatus 95 is to be removed by reversing the operation of inserting them, and the washing-down process resumed; otherwise the boring will be continued, as desired.

During the process of construction described 105 it is of vital importance that the stream be kept flowing down inside the pipe for keeping the tools from becoming choked with sand, &c., and also to prevent the earth, &c., from settling about the exterior surface of the pipe and preventing their further movement, should it become necessary to do so. In placing "jars" or drop-drills into the pipes the operation is 110 the same, excepting that the sliding clamping-gland m, Sheet 2, Fig. 5, must be provided and 115 so adjusted as to move with the cable or rope and protect it as it rises or falls. When the pipes have reached the solid formation and have been properly joined thereto, the water may be partially or wholly shut down, when 120 the pipes will serve as a casing within which ordinary drilling operations may be conducted, either with or without the aid of the split sleeve-couplings referred to.

I am aware that holes have been washed out 125 in sand, and I am also aware that wells have been formed by driving down tubing in and through beds of sand, clay, marl, &c.; but these all are tedious and expensive operations, and extremely uncertain as to results, and generally 130 require several lines of pipes telescoped one inside the other, and even with all methods now in use it is impossible to sink wells to any great depth through sand, gravel, &c., and

particularly when an occasional boulder or rock has to be encountered.

What I claim is—

1. The combination of two three-way-split sleeve-couplings, C C, with two or more lengths of pipe, as and for the purposes specified. 5
2. The two three-way-split sleeve-couplings C C, each having suitable water-conduits, in combination with two or more lengths of pipe, 10 as and for the purposes specified.
3. The two three-way-split sleeve-couplings C C, each having suitable water-conduits, in combination with two or more lengths of pipe, said sleeve-couplings being coupled together 15 with suitable tie-rods, as and for the purposes described.
4. The within-described method of constructing wells, consisting in forcing a fluid through a pipe against the substance to be removed, then, while continuing the flow of the fluid, coupling a section of pipe to the pipe first used, and afterward changing the initial 20 inflow of the fluid from the first into the second section of pipe, from whence it is passed into the first section, and repeating such steps 25 with successive sections until the desired end is reached, substantially as and for the purpose set forth.
5. In the construction of wells under a continuous flow of a fluid, the method of constructing a line of casing or tubing for the passage of the fluid, consisting in connecting two sections of pipe by a coupling provided 30 with an inlet for the fluid and a valve for closing the same, and securing to the upper end 35 of the lower section of pipe, between it and the first-named coupling, an internally-threaded coupling, having an inner projection flush with the inner wall of the pipe, then closing the fluid-inlet in the coupling and simultaneously directing the fluid into the upper section of the pipe, and then, while the fluid is flowing through the same into the lower section of the pipe, forcing the lower end of the upper section down into the said second or intermediate coupling against the projection in said coupling, whereby a connection between the two sections of pipe is effected without stopping the flow of the fluid and without internal obstructing projections, substantially as 40 45 50 set forth.
6. The method of constructing wells consisting in drilling through a pipe, the substance to be removed, and at the same time maintaining a continuous downward flow of a fluid through said pipe, substantially as and for the purpose set forth. 55
7. The combination of the pipe, the drilling or boring device therein, means for maintaining a downward flow of a fluid through said pipe, and a valve to prevent the escape of the fluid through the drilling device, substantially as and for the purpose set forth. 60

In testimony whereof I have hereunto set my hand in the presence of two subscribing witnesses. 65
